CUTTING APPARATUS

William H. Ford, East Longmeadow, Mass., assignor to Milton Bradley Company, Springfield, Mass., a corporation of Massachusetts

Application October 17, 1936, Serial No. 106,100

2 Claims. (Cl. 164—44)

This invention relates to improvements in cutting apparatus and is directed more particularly to improvements in paper-cutting devices.

It is one of the principal objects of the invention to provide a novel cutting device which includes a pair of co-acting shearing members, one of which at least is movable, and means to urge the movable member out of shearing relation with the other member. The construction of the invention is simple in form so as to be economical to manufacture and easy and efficient in operation and is so arranged as to obviate the likelihood of the operator's becoming injured.

Various other objects and advantages of the invention will become more apparent after a reading of the following description and reference will be had to the accompanying drawing wherein:

Fig. 1 is a plan view of the device of the invention;

Fig. 2 is a side elevational view of the device shown in Fig. 1; and

Fig. 3 is a partial plan view on an enlarged scale to explain certain details of construction.

Referring now to the drawing more in detail the invention will be fully described.

A base or supporting member 2 is provided and this preferably consists of a table-like member having a substantially flat surface for supporting the paper or other material which is to be cut. A stationary knife member 4 is associated with the supporting member and this may be secured thereto as by screws 6 or the like along a marginal edge of the base 2, as shown.

If desired the base or board member 2 may have legs 8 as shown. It is usual to associate with the support a rule 10 such as shown but this does not comprise an essential part of the invention.

A movable knife member 12 is provided and this is arranged for moving into and out of shearing relation with the stationary knife as will appear. It has a cutting edge 13 and may have a handle 14.

A bracket 20 is associated with base 2 and there is a shaft 22 rotatable therein. The shaft carries the knife member 12 so that the latter is hingedly connected to the base for swinging between an upper non-shearing position and a lower shearing position. A stop 16 may be provided to limit the downward movement of the member 12.

I preferably provide a spring such as 24 around shaft 22 and between an enlarged part 26 and bracket 20 for urging the knife 12 inwardly to-

wards knife 4. At the same time an adjustable bolt 23 extends through the rear end part of knife 12 and has its inner end in engagement with a cam surface 21 provided on bracket 20. The bolt 23 and cam surface 21 are arranged to co-operate with spring 24 to bring about the proper shearing action of the knives when the movable knife is swung downwardly.

It will be appreciated that it is necessary to move the knife 12 upwardly after each downward shearing stroke. It is one of the features of this invention that means is provided whereby the knife 12 automatically lifts upwardly when released after shearing.

To this end I provide a separate coil spring 15 member 28 which surrounds shaft 22 and is preferably disposed between the bracket 20 and rear end part of the knife 12. This spring 28 has one end part 30 secured to the bracket 20 or base 2 and its other end 29 in engagement with the knife 12. With this arrangement, the downward strokes of the lever set up tension in spring 28 which urges the knife member 12 upwardly out of shearing relation when released.

It will be seen that in this way the knife is substantially self-lifting and moves upwardly out of the way after the knife 12 has done its work. This leaves the operator with both hands to work with and does away with the possibility of injury. The adjustment is such and the parts are so arranged that the strokes are smooth and accurate with a minimum of objectionable friction.

While I have described the invention in great detail and with respect to a preferred form thereof, it is not desired to be limited thereto since many changes and modifications may be made therein without departing from the spirit and scope of the invention. What it is desired to claim and secure by Letters Patent of the United States is:

1. A cutting device of the class described comprising in combination, a support, a stationary knife on said support, a rotatable and reciprocable shaft associated with said support, a movable knife carried by said shaft for swinging downwardly towards said stationary knife and upwardly away therefrom as said shaft rotates, a coil spring extending around said shaft and urging the shaft to reciprocate in one direction 45 to bring said movable knife against said stationary knife, and another coil spring extending around said shaft having a part in engagement with said movable knife urging the knife upwardly and outwardly away from said stationary knife, 50 55

all adapted and arranged whereby said movable knife is automatically caused to act against said stationary knife as the former is moved downwardly by manual engagement therewith and to move upwardly out of engagement with said stationary knife when released from manual engagement.

5. 2. A cutting device of the class described comprising in combination, a support, a stationary knife on said support, a bracket on said support, a shaft rotatable and reciprocable in said bracket, a movable knife carried by said shaft for swinging downwardly towards said stationary knife as said shaft rotates in one direction and 10 upwardly away therefrom as said shaft rotates 15

in an opposite direction, a coil spring around said shaft urging it to reciprocate inwardly and move said movable knife inwardly against said stationary knife, and another coil spring around said shaft having a part in engagement with said movable knife urging the knife upwardly and outwardly away from said stationary knife, all adapted and arranged whereby said movable knife is automatically caused to act against said stationary knife as the former is moved downwardly by manual engagement therewith and to move upwardly out of engagement with said stationary knife when released from manual engagement.
